PROCESS OF SULPHATION

Max Engelmann, Wilmington, Del., assignor to
E. I. du Pont de Nemours & Company, Wil-
mington, Del., a corporation of Delaware

No Drawing. Application August 27, 1938,
Serial No. 227,062

7 Claims. (Cl. 260—400)

This invention relates to a new method of sulphating aliphatic compounds which contain 8 or more carbon atoms and a hydroxyl group attached to a secondary or tertiary carbon atom and more particularly to the sulphation of said compounds in the presence of a lower alkyl ester of an aliphatic monocarboxylic acid containing from 1 to 8 carbon atoms.

This invention has as an object an improved method of sulphating aliphatic compounds which contain 8 or more carbon atoms and a hydroxyl group attached to a secondary or tertiary carbon atom. A further object is to sulphate said aliphatic compounds in the presence of a cheap diluent which does not need to be recovered and which imparts a pleasant odor to the sulphation product. A still further object is to employ a diluent in the sulphation procedure which tends to prevent side reactions and permits one to obtain high yields of sulphation products which have an improved solubility and a better physical appearance. Other objects will appear hereinafter.

These objects are accomplished by the following invention which relates to the sulphation of aliphatic compounds which contain 8 or more carbon atoms and a hydroxyl group attached to a secondary or tertiary carbon atom in the presence of an alkyl ester of an aliphatic monocarboxylic acid containing from 1 to 8 carbon atoms wherein the alkyl group in said ester contains from 1 to 8 carbon atoms.

The invention is illustrated, but not limited, by the following examples in which the parts are by weight.

Example 1

50 parts of pentadecanol-8 were dissolved in 46.4 parts of ethyl acetate. 30.6 parts of chlorosulphonic acid were slowly added at a temperature of 0° to 10° C. over a period of 1½ hours. At the end of this time a test drop gave a clear solution in water. The sulphation mass was poured into an aqueous sodium hydroxide solution. Two layers formed. The upper oily layer contained the sodium pentadecyl-8 sulphate. On evaporating with gentle heating on the steam bath a light colored waxy solid showing excellent water solubility and high wetting-out action was obtained.

Example 2

50 parts of pentadecanol-8 were dissolved in 70 parts of methyl acetate and treated as in Example 1 with 34 parts of chlorosulphonic acid. A product with good solubility and high wetting-out action was obtained.

Example 3

169 parts of chlorosulphonic acid were dissolved in 161 parts of propyl acetate. 300 parts of

molten pentadecanol-8 were added over a period of two hours at —10° to —5° C. The product was worked up as in Example 1.

Example 4

200 parts of 1,12-octadecanediol were dissolved in 330 parts of ethyl acetate. 197 parts of chlorosulphonic acid were added over a period of two hours. The product was worked up as in Example 1. The octadecanediol was converted to the extent of about 85% into the corresponding disulphate.

Example 5

30 parts of alpha hydroxy stearic acid were mixed with 50 parts of methyl acetate. 15 parts of chlorosulphonic acid were slowly added while stirring at a temperature of 25° to 30° C. During the sulphation process the acid went into solution. After further agitation for ½ hour a test drop gave a clear solution in water. The sulphation mass was poured into 200 parts of a 10% aqueous solution of sodium hydroxide. After the addition of about 20 parts of sodium chloride two layers were formed. The upper layer contained the di-sodium salt of the sulphate ester of hydroxy stearic acid. To isolate the sodium salt in dry form the lower layer was decanted off and the remaining very viscous mass dried on a steambath. The residue was a waxy solid showing excellent water solubility. The water solution showed all the characteristics of a solution of a surface active compound. It was not precipitated from solution either by acids or by solutions of calcium or magnesium salts.

Any alkyl ester of an aliphatic monocarboxylic acid containing from 1 to 8 carbon atoms wherein the alkyl group in said ester contains from 1 to 8 carbon atoms may be used as a diluent in the sulphation reaction. In other words, the use of the methyl, ethyl, propyl, butyl, amyl, hexyl, heptyl, and octyl esters of formic, acetic, propionic, butyric, valeric, caproic, heptoic, and caprylic acids is contemplated. High molecular weight esters may be employed such as octyl acetate, butyl propionate and ethyl caprylate. However, lower molecular weight esters such as methyl formate, ethyl formate, propyl formate, methyl acetate, ethyl acetate, and propyl acetate are cheaper, and hence from an economic viewpoint, they are more feasible to use. Propyl acetate is the preferred diluent for use in the sulphation of pentadecanol-8.

Chlorosulphonic acid is the preferred sulphating agent but other strong sulphating agents such as oleum, sulphuric monohydrate, bromosulphonic acid and sodium chlorosulphonate may be employed.

The temperature at which the reaction is run may be varied over wide limits, the optimum

temperature being dependent upon the nature of the hydroxy compound being sulphated. Thus, while temperatures of from -30° to 35° C. are preferred, lower and higher temperatures may be employed in this reaction.

The method of carrying out the reaction with respect to the order of addition of the reagents also lends itself to several variations. The chlorosulphonic acid can be dissolved in the ester 10 and added to the hydroxy compound; the hydroxy compound can be added to a solution of chlorosulphonic acid in the ester, or the chlorosulphonic acid can be added to a solution of the hydroxy compound in the ester.

15 The procedure described in this specification is useful for sulphating any aliphatic compound which contains 8 or more carbon atoms and a hydroxyl group attached to a secondary or tertiary carbon atom. This invention is most useful 20 in the preparation of secondary alkyl sulphates containing 8 or more carbon atoms by sulphation of secondary aliphatic alcohols containing 8 or more carbon atoms. Secondary alcohols which may be sulphated in accordance with the present 25 invention include tridecanol-7, 3,9-diethyl tridecanol-6, 5,11-diethyl pentadecanol-8, octanol-2, pentadecanol-4, and pentadecanol-8. Tertiary alcohols which can be sulphated according to the processes disclosed herein include diheptyl ethyl carbinol and dioctyl methyl carbinol. Other aliphatic compounds which contain a hydroxyl group attached to a secondary or tertiary carbon atom which can be sulphated by the methods disclosed herein include ethers such as 12-hydroxy octadecyl methyl ether and alpha, alpha' bis(2-ethylhexyl) glycerine ether; hydroxy ketones such as capryloin; hydroxy acids and their esters such as alpha hydroxy stearic acid, the methyl ester of alpha hydroxy stearic acid, 40 ricinoleic acid, methyl ricinoleate, the lauryl ester of alpha hydroxy propionic acid, bis(2-ethylhexyl) malate, triethyl citrate, and dihexyl tartrate.

45 It has been found that the presence of these esters exerts a profound influence upon the reaction of chlorosulphonic acid upon hydroxy compounds. It is not clear just what is the mechanism of the reaction, but it is apparent that the ester does not function as an inert diluent. Thus 50 in the case of secondary alcohols, treatment with the usual sulphating agents, such as chlorosulphonic acid, leads to dehydration of the alcohol and the formation of valueless water-insoluble, dark colored products. If secondary alcohols are 55 treated with chlorosulphonic acid in the presence of typical diluents such as carbon tetrachloride, ethylene dichloride, or chloroform, side reactions leading to water-insoluble, dark colored products are obtained. When, however, secondary alcohols 60 are reacted according to the present invention, smooth and efficient conversion of the alcohols into alkyl sulphates takes place.

65 This application covers a particularly efficient and smooth method for sulphating aliphatic compounds which contain 8 or more carbon atoms and a hydroxyl group attached to a secondary or tertiary carbon atom. The mildness of the reaction makes it applicable to very labile compounds which ordinarily undergo undesirable side reactions when treated with sulphating agents. In 70 spite of the mildness of the reaction, high yields

and accordingly very pure products can be obtained.

Secondary and tertiary aliphatic alcohols cannot be satisfactorily sulphated by the ordinary means such as chloro-sulphonic acid or sulphuric acid alone or in the presence of inert diluents. However, when these alcohols are treated in the presence of aliphatic esters with chlorosulphonic acid, smooth and efficient sulphation is obtained. Since these esters are cheap diluents, it is not necessary to recover them. They may be permitted to remain in the sulphation product to which they will impart a pleasant odor.

The above description and examples are intended to be illustrative only and not to limit the scope of the invention. Any departure therefrom which conforms to the spirit of the invention is intended to be included within the scope of the appended claims.

I claim:

1. A method of sulphating a saturated aliphatic compound which contains at least 8 carbon atoms and a hydroxyl group attached to a secondary carbon atom which comprises reacting said aliphatic compound with a strong sulphating agent 25 in the presence of an alkyl ester of an aliphatic monocarboxylic acid containing from 1 to 8 carbon atoms wherein the alkyl group in said ester contains from 1 to 8 carbon atoms.

2. A method of preparing a secondary alkyl 30 sulphate containing at least 8 carbon atoms which comprises reacting a secondary aliphatic alcohol containing at least 8 carbon atoms with chlorosulphonic acid in the presence of an ester selected from the group consisting of the methyl, 35 ethyl, and propyl esters of formic and acetic acids.

3. A method of preparing pentadecyl-8 sulphate which comprises reacting pentadecanol-8 with chlorosulphonic acid in the presence of 40 propyl acetate.

4. A method of preparing pentadecyl-8 sulphate which comprises reacting pentadecanol-8 with chlorosulphonic acid in the presence of an ester selected from the group consisting of the 45 methyl, ethyl, and propyl esters of formic and acetic acids.

5. A method of preparing pentadecyl-8 sulphate which comprises reacting pentadecanol-8 with chlorosulphonic acid in the presence of 50 ethyl acetate.

6. A method of preparing an alkyl sulphate containing at least eight carbon atoms which comprises reacting an alcohol selected from the group consisting of secondary and tertiary aliphatic alcohols containing at least eight carbon atoms with a strong sulphating agent in the presence of an alkyl ester of an aliphatic monocarboxylic acid containing from one to eight carbon atoms where in the alkyl group in said ester 60 contains from one to eight carbon atoms.

7. A method of preparing an alkyl sulphate containing at least eight carbon atoms which comprises reacting an alcohol selected from the group consisting of secondary and tertiary aliphatic alcohols containing at least eight carbon atoms with chlorosulphonic acid in the presence of an ester selected from the group consisting of the methyl, ethyl, and propyl esters of formic and acetic acids.

MAX ENGELMANN.
